UNITED STATES PATENT OFFICE.

HENRY G. ROTH, OF MINNEAPOLIS, MINNESOTA.

DISPLAY-FIXTURE.

SPECIFICATION forming part of Letters Patent No. 678,690, dated July 16, 1901.

Application filed January 24, 1901. Serial No. 44,554. (No model.)

To all whom it may concern:

Be it known that I, HENRY G. ROTH, a citizen of the United States, residing at Minneapolis, in the county of Hennepin and State 5 of Minnesota, have invented certain new and useful Improvements in Display-Fixtures; and I do hereby declare the following to be a full, clear, and exact description of the invention, such as will enable others skilled in the 10 art to which it appertains to make and use the same.

My present invention has for its object to provide a simple and efficient display-fixture for retail stores and other places which may 15 be readily put up and knocked down and packed in small space for storage and shipment.

To the above ends the invention consists of the novel devices and combinations of 20 devices hereinafter described, and defined in the claims.

The invention is illustrated in the accompanying drawings, wherein like characters indicate like parts throughout the several views.

25 Figure 1 is a view in side elevation showing a section of fixture constructed in accordance with my present invention applied in working position. Fig. 2 is a front elevation of the fixture shown in Fig. 1. Fig. 3 is a 30 plan view showing the sections of the fixture separated and laid out flat in their relative positions. Fig. 4 is a horizontal section approximately on the line $x^4 x^4$ of Fig. 2, some parts being broken away. Fig. 5 is a vertical section on the line $x^5 x^5$ of Fig. 3. Fig. 6 is an enlarged section on the line $x^6 x^6$ of Fig. 3, and Fig. 7 is a detail view in plan showing one of the so-called "binders."

35 In this preferred construction the body of 40 the fixture is made up of a plurality of flexible sheets of material, preferably of thin spring sheet metal. In the drawings the said body also comprises a lower end sheet-section 2, which may be either of spring or any other 45 suitable material. The sections 1 and 2 are connected at their adjoining edges by hinges 3, preferably afforded by canvas strips suitably secured to the said sections.

For coöperation with the sections 1 and 2, 50 I provide channel-like marginal strips 4 and 5, the former of which are curved and the latter of which is shown as straight. The

manner in which the several strips 4 may be curved to produce the design illustrated in Fig. 1 is best illustrated in Fig. 3. These 55 marginal strips may be given any desired curve; but they must have sufficient stiffness to maintain their curved form and give the proper curves to the plate-sections 1 when they are applied to the side edges thereof, as 60 indicated in Fig. 2.

It will often be desirable to secure pictures or printed cards or sheets to the outer faces of the sections 1, and when this is to be done such cards or sheets are applied, as indicated 65 at 6 in Fig. 4, the marginal channel-pieces 4 being slipped over the edges of the same as well as over the edges of the said plates 1. To more firmly tie together the channel-strips 4 and hold them in working positions on the 70 plate-sections 1, binding-strips 7 are employed. These binding-strips 7 have hooked ends 8, which are adapted to engage over the ends of the channel-strips 4, as shown in Figs. 2 and 4.

The sections 1 if made of cardboard or even 75 when made of cheap metal may of course have the pictures or advertising matter printed, painted, or otherwise produced directly on the exposed surfaces thereof.

80 It is evident that a fixture of the above character will be of small cost, of very light weight, and may be very easily put together and knocked down. Furthermore, it will pack in very small space.

85 The fixture above illustrated may be bent into a great many different forms to form different designs of fixture. When formed as indicated in Fig. 1, it may be detachably secured to the wall, as indicated by several nails 90 or other suitable devices.

It will be understood that the invention above described is capable of considerable modification within the scope of my invention.

What I claim, and desire to secure by Letters Patent of the United States, is as follows:

95 1. A knockdown fixture comprising a plurality of flexible plates, and permanently-curved marginal strips, engageable with edges of said plates to hold the same curved, substantially as described.

100 2. A knockdown fixture comprising a plurality of flexible plates, and stiff marginal channel-strips of curved form, engageable

with the edges of said plates to hold the same curved, and which curved plates are adapted to form various configurations substantially as described.

5. 3. A knockdown display-fixture comprising a plurality of spring-plates connected by hinged joints, and stiff marginal channel-strips, certain of which are curved and are engageable with the edges of certain of said plates to hold the same curved, substantially as described.

4. In a display-fixture, the combination with a plate and a show-card of approximately the same width, of channel-strips of spring material adapted to be sprung over the edges of said plates and board, to detachably hold

the same together and to stiffen and determine the form of said parts, substantially as described.

5. A display-fixture comprising a flexible plate, a pair of marginal channel-strips engageable with the edges of said plate, and a binder having hooked ends detachably engageable over said channel-strips, substantially as described. 25

In testimony whereof I affix my signature in presence of two witnesses.

HENRY G. ROTH.
